UNITED STATES PATENT OFFICE.

WILLIAM B. McCARTHY, OF MILFORD, CONNECTICUT, ASSIGNOR TO THE ROSTAND MANUFACTURING COMPANY, OF MILFORD, CONNECTICUT, A CORPORATION OF CONNECTICUT.

DESIGN FOR TUBING FOR AUTOMOBILE-WINDSHIELD FRAMES.

59,367.

Specification for Design.

Patented Oct. 11, 1921.

Application filed October 15, 1920. Serial No. 417,249. Term of patent 14 years.

To all whom it may concern:

Be it known that I, W. B. McCARTHY, a citizen of the United States, residing at Milford, in the county of New Haven, State of Connecticut, have invented a new, original, and ornamental Design for Tubing for Automobile-Windshield Frames, of which the following is a specification, reference being had to the accompanying drawing, forming part thereof.

Figure 1 is a perspective view of a piece of tubing showing my new design.

Fig. 2 is an end view of the same.

I claim:

The ornamental design for tubing for automobile windshield frames, as shown.

W. B. McCARTHY.
